DESIGN FOR AN ENVELOPE

Horace W. Davis, Pittsfield, Mass., assignor to Eaton Paper Corporation, Pittsfield, Mass., a corporation of Massachusetts

Application November 4, 1939, Serial No. 88,052

Term of patent 14 years

To all whom it may concern:

Be it known that I, Horace W. Davis, a citizen of the United States, residing at Pittsfield, in the county of Berkshire and State of Massachusetts, have invented a new, original, and ornamental Design for an Envelope, of which the following is a specification, reference being had to the accompanying drawing, forming a part thereof.

Referring to the drawing:

Fig. 1 is a front view of an envelope showing my new design; and

Fig. 2 is a rear view thereof.

The drawing is lined to show the colors red and blue.

I claim:

The ornamental design for an envelope, as shown and described.

HORACE W. DAVIS.
